BURIAL VAULT

Edward J. Lager, Davenport, Iowa, assignor to Lager
Mfg. & Supply Co., Bettendorf, Iowa, a corporation of Iowa

Application April 2, 1959, Serial No. 55,318

Term of patent 14 years

(Cl. D19—1)

FIG. 1

FIG. 3

Fig. 1 is a perspective view of a burial vault, showing my new design;

Fig. 2 is an opposite perspective view; and
Fig. 3 is a top plan view thereof.

I claim:

The ornamental design for a burial vault, substantially as shown.
